UNITED STATES PATENT OFFICE.

CHARLES E. GREENWALD, OF SPOKANE, WASHINGTON.

BELT.

1,327,035.

Specification of Letters Patent.

Patented Jan. 6, 1920.

Application filed September 21, 1918. Serial No. 255,023.

To all whom it may concern:

Be it known that I, CHARLES E. GREENWALD, a citizen of the United States, residing at Spokane, in the county of Spokane 5 and State of Washington, have invented certain new and useful Improvements in Belts, of which the following is a specification.

The present invention relates to an improved belt for personal wear, specially 10 adapted for men's wear, and designed to be substituted for the customary pair of suspenders in supporting the trousers at the waistband and over the hips of the wearer.

The primary object of the invention is the 15 provision of a belt of this character that preserves the usual neat and attractive appearance of belts of this type and combines therewith the added function of positively supporting the trousers over the hips of the 20 wearer, and that in such manner as to be both comfortable and convenient for the wearer. One of the specially meritorious 25 features of the belt is the fact that the added elements do not change the appearance of the belt; another attractive factor in the invention is the fact that the added elements perform their function of supporting the belt on the hips without in any way distorting or disarranging the belt or the trousers 30 which they support, but rather the belt itself affords means for keeping and maintaining the trousers in proper position about the waist of the wearer; and these added characteristics and their results are attained with 35 but slightly increased cost of production of the belt.

In the accompanying drawings one complete example, and a modified form of the invention are illustrated, and arranged and 40 constructed according to the best modes so far devised for the practical application of the principles of the invention, and the physical embodiment illustrated in the drawings, has proven highly satisfactory 45 and gratifying to numerous wearers of the belt as improved in accordance with the present invention.

Figure 1 is a perspective view of a belt according to my invention, showing it in position as when used by a wearer.

Fig. 2 is an enlarged, transverse sectional view showing the belt passed through one of the loops or straps at the waistband of a pair of trousers.

Fig. 3 illustrates a modified form of the

belt wherein the reinforcement extends below the lower edge of the belt.

In the physical embodiment of my invention the drawings show a belt 1 of usual style and shape, and it will readily be apparent that the belt may be one already in use, or the invention may be applied for use during the manufacture of the new belt. The usual buckle 2 at one end of the belt, and the free end 3 with perforations 4 for 60 the tongue or prong 5, serve to secure the parts, and the fixed loops 6 6 are present for the reception and retention of the end 3.

The invention consists essentially in providing the belt, at its interior face, and at 70 opposite lateral points, with a pair of reinforcements or strips 7, 7, that are crescent shape and taper down to a thin edge, stitches 8 being employed to secure the strip as well as its thin edges 9 to the inner face of the 75 belt. The belt of course is flexible, and the reinforcements or filler strips 7 are also flexible, but because of their added thickness, these strips render the belt at the sides, where the belt rests on the hips, less flexible 80 than at other points throughout the circumference of the belt.

In wearing the belt it is used in customary manner, around the waistband 10 of the trousers and passed through the loops 11, 85 as shown in Fig. 2, and in Fig. 3 a modified form of the invention is shown wherein the belt 1^a has the filler strip 7^a extending below the edge of the belt, but the relation to the waistband 10^a and the loop 11^a of the 90 trousers is the same.

In the two sectional views it will be apparent that the two strips 7 rest over the hips as indicated by the curves of the trousers material, and the entire belt is comfortably seated about the waistband of the 95 wearer.

In putting on the belt, the wearer draws the buckle to the usual tension for comfort, and the natural curve or contour of the belt 100 around the waist is not changed or disturbed from the old style, but as the result of the presence of the strips 7, 7, the diameter of the belt, from the inner walls of its sides or from the inner faces of the strips, is decreased, and less than would be the case with the unaltered belt, and these hip-strips 7 firmly hold and grip the body of the wearer just over the hips, holding the trousers up 105 in proper position.

Thus the hip strips, which are not visible to the observer, are satisfactorily felt by the wearer, whose belt is thus left slightly slack so far as the belt itself is concerned, with its accompanying comfort and convenience, while the strips perform, exclusively, the functions of gripping the wearer, at the hips only, to support the trousers.

In the modified form of Fig. 3 it is sometimes desirable and preferable that the strips project below the belt as indicated, and in some instances, this form of the invention is used instead of the first form illustrated.

While the strips have been described as of leather, it will readily be understood that other satisfactory and suitable material may be substituted therefor, and the form and

dimensions of the strips may be changed, without departing from the scope of the invention.

Claim—

A garment supporting flexible belt for personal wear having attached thereto at its hip portions strips with tapering ends, each of said strips made of relatively rigid material and having a cross sectional area intermediate its ends of substantially greater thickness than the material of the belt, said strips merging into the belt at the points of attachment, and said belt adapted, through the instrumentality of these strips to grip the body only at the sides of the wearer above the hips.

In testimony whereof I affix my signature.

CHARLES E. GREENWALD.
